UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

VOLUTE BRAKE MECHANISM

Application filed June 3, 1927. Serial No. 196,347.

The invention relates to brake mechanism for railway cars.

The principal object of the invention, generally stated, is to provide a hand brake of such construction as to permit and facilitate the application of a high degree of tension upon the brake beams and consequently the brake shoes of a car braking mechanism or system.

It is well known that in the ordinary type of hand brake in which there is provided a drum or the like about and onto which the chain or other flexible member of the brake mechanism is wound, the winding rate may be and usually is the same at all stages during the application of the brakes, a condition which does not result in the most efficient operation. Accordingly, I have designed the present invention which has for an important object the provision of a brake chain winding mechanism of such construction that the rate at which the chain or other flexible member is wound in decreases as the slack is taken up and the tension increased, there being consequently a greater leverage as greater resistance is met.

An important object is to provide a novel bracket structure or mounting for the drum and associated parts, the mounting including detachable bearing means facilitating assembly.

Another object of the invention is to provide a brake mechanism of this character which is free from the disadvantages inherent to the use of worm gearing often provided as a means for obtaining a high leverage.

Inasmuch as the shafts and chains for brake mechanism must be of substantial dimensions to possess the requisite strength and as it is impractical to employ large winding wheels, the amount of pull that can be produced by hand power is rather limited except by providing an elaborate reducing gear mechanism of such complexity and weight, as well as size, as to preclude its successful employment. As it therefore becomes necessary to keep the size of the parts within reasonable limits while providing means for multiplying the applied power, I

have conceived the present invention which has for a still more specific object the provision of a volute drum which is manually rotated for winding the brake setting chain, the drum, shaft or staff and the other combined and associated parts of the mechanism being all of such nature as to be simple and inexpensive to manufacture, easy to install in old or new equipment, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a side elevation of the device.

Figure 2 is a top plan view thereof with the operating shaft removed from its socket.

Figure 3 is a horizontal cross section taken on the line 3—3 of Figure 1 and illustrating one means for rotatably mounting the lower end of the volute drum.

Figure 4 is a fragmentary side elevation illustrating a modified means for maintaining the lower end of the drum in journalized position.

Figure 5 is a detail horizontal section taken on the line 5—5 of Figure 4.

Referring more particularly to the drawings, I have shown the mounting for the brake operating mechanism as comprising an angular bracket indicated generally by the numeral 1, this bracket being capable of formation as a single casting though there are naturally no limitations in this particular inasmuch as it could be constructed of several different parts secured together in any preferred manner. Describing the bracket in detail, it may be said to include a main or upright portion 2 which terminates at its upper and lower ends in substantially horizontal arm portions 3 and 4, respectively, the former of which serves as a base for attachment to a car or the like and is formed with a bearing sleeve 5 and the latter of which may be of substantially U-shaped yoke form including arms 6. The bracket 1 is in-

tended to constitute the sole support or mounting for the winding member to be described and the upper arm 3 is therefore represented as formed between the upright portion 2 and the bearing sleeve 5 with a bearing 7 which may actually consist simply of an opening 8 surrounded by an enlarged boss. As a matter of fact, details such as these, together with other details such as the provision of reinforcing webs or ribs at the points of greatest strain, may be varied within wide limits. The lower arm 4 carries a bearing structure, to be described, alining with the bearing 7.

15. The winding drum is indicated generally at 9 and is here shown as of volute form or provided with a volute web or rib 10, though it should be understood that one of a different variety may be used. At one end this 20 drum has a reduced extension 11 constituting a trunnion journaled within the opening 8 in the bearing 7, this end being formed at the base of said extension with a flange 12 constituting a stop or abutment upon which is seated the flanged end 13 of a gear 14. The 25 other end of the drum is formed with an inverted frusto-conical or tapered bearing portion 15 which merges into a reduced extension 16 and both of which constitute a trunnion, the tapered portion and extension being journaled within a corresponding opening in a block-like bearing 17 located within the confines of the yoke including the arms 6, this bearing member 17 being retained in 30 position as for instance by means of a rivet 18 or the like passing through it and the arms 6. An alternative mounting for the lower end of the drum will be described hereinafter though this is a form which will give entire 35 satisfaction.

The drum 9 is adapted to have the brake setting chain, not shown, secured thereto and wrapped thereabout, the point of connection of the chain being preferably at the lower 40 end of the drum for which reason the lower end is shown as having a slot 19 therein for receiving the endmost link of the chain or a ring carried by the chain. While it is true that any suitable means might be provided for actually securing the chain to the drum, the holding means is here represented as including a pin 20 traversing the slot and held against displacement as by means of a cotter 21. This lower end of the drum to which the 45 chain is secured is of the largest diameter inasmuch as comparatively small leverage is needed at first when winding in the chain, the initial or preliminary movement being principally to take up slack. The drum may conveniently decrease in effective radius from the lower end to the upper and there may even be a substantially zero effective radius at or near the upper end if such is found advisable.

50. The operating means for imparting rotary

movement to the drum preferably comprises a rotatable member 22 journaled within the bearing sleeve 5 and having its lower end formed with teeth 23 meshing with the gear 14. Immediately above the bearing sleeve 5 the member 22 may have an outstanding flange 24 for the purpose of preventing it from longitudinal displacement, and the upper end of the member 23 is or may be formed with a socket 25 within which is removably engaged the tapered lower end of the manually operable brake staff 26 equipped with the usual hand wheel or the like, not shown. To provide a driving connection between the member 22 and the shaft 26, it is preferable that the socket and tapered end of the staff be non-circular or angular in cross section as illustrated in Figure 2 though it is of course conceivable that a different arrangement might be provided if desired. The staff may be secured to the operating member 22 by inserting a pin, not shown, within suitable holes 27 in the member 22 and tapered end of the staff. These and other minor variations may readily suggest themselves depending upon circumstances that may arise or conditions to be met. To hold the member 22 in the proper operative relation to the bearing sleeve 5 and gear 14, I have found it convenient to provide a transverse element such as the rivet 28 passing through the sleeve 5 and intersecting a peripheral groove 29 in the member 22. Clearly, this member 28 cannot interfere with rotation of the member 22, its sole function being to prevent longitudinal movement of the latter with respect to its bearing sleeve 5.

Instead of providing the bearing block 17 above described, I may make use of the alternative mounting for the lower end of the drum as illustrated in Figures 4 and 5. Referring to these views in detail, I have shown the bracket member as having its lower end formed with an arm 30 terminating in a split sleeve 31 which has its free edges initially extended outwardly as shown by dotted lines in Figure 5. The lower end of the drum is of exactly the same form as above described and is journaled within a block-like bearing member 32 formed with a reduced portion 33 received within the split sleeve 31, this reduced portion having recesses or cut-away portions 34 at opposite sides of its center defining an outstanding rib 35.

In assembling the form of the invention embodying the modified lower bearing for the lower end of the drum, the bearing member 32 is inserted within the split sleeve 31 and the outwardly extending free edges of the sleeve, which edges are represented at 36, are then bent inwardly toward each other so as to engage within the recesses or cut-away portions 34 in the bearing member, the rib 35 being located between the confronting edges of these bent portions.

In operation, it will be apparent that when the staff 26 is turned, as by means of the usual hand wheel, the teeth 23 on the rotary member 22 will operate to drive the gear 14 and effect rotation of the drum 9. The chain, not shown, which is attached to the lower and larger end of the drum will then of course be wound upon it within the successive convolutions. As the lower end is the larger, the initial movement of the chain will be considerable so that the slack will be quickly taken up. As the chain leaves the lowermost convolution and is wound onto the next, the rate of movement thereof is decreased but the leverage greatly increased so that by means of the expenditure of no more than the usual amount of time, effort and labor the brake mechanism to be operated is applied or set sufficiently and powerfully so as to insure the proper braking action. While it is not illustrated, it will be understood that use may be made of the usual or any suitable pawl and ratchet mechanism for preventing premature unwinding of the chain and release of the brakes.

From the foregoing description and a study of the drawings it will be apparent that I have thus provided a brake operating mechanism which is not only simple and inexpensive in construction and easy to install, but light in weight and compact in form, there being an avoidance of any excessively heavy, large or cumbersome parts. It is believed that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a brake operating mechanism, a support comprising a base apertured to provide a bearing, a depending arm with a bifurcated end underlying the apertured portion of the base, a drum journaled at its upper end within the apertured portion of the base and provided with means for attachment of a flexible member thereto, the drum having a flange and a plurality of convolutions constituting a seat to receive the flexible member, and a bearing block embraced by and connected to the bifurcated end of the support arm and serving to rotatably mount the lower end of the drum.

2. In a brake operating mechanism, a support, a drum journaled at its upper end with-

in the support and provided with means for attachment of a flexible member thereto, the drum having a flange and a plurality of convolutions constituting a seat to receive the flexible member, that portion of the drum to which the flexible member is attached being the larger and the successive convolutions being reduced in diameter, an arm extending from said support and formed with an end underlying said drum, bifurcated and embracing the lower end thereof, and a bearing block for said lower end held in the bifurcated end of the arm.

3. In a brake operating mechanism, a support, a drum journaled within the support at both ends and provided with means for attachment of a flexible member thereto, the connection at one end of said drum comprising a bearing block separable from said support to facilitate assembly of the mechanism, the drum having a flange and a plurality of convolutions constituting a seat to receive the flexible member, a manually operable member, and gear connections between said manually operable member and the drum.

4. In a brake operating mechanism, a supporting bracket having upper and lower bearings therein, said lower bearing comprising a removable bearing block embraced by a bifurcated portion of the bracket, a drum having its ends journaled within the bearings, said drum being adapted to have a flexible brake applying element secured thereto and having a continuous flange defining a seat for the reception of the flexible element, and gear means for rotating the drum from a remote point.

5. In a brake operating mechanism, a supporting bracket having an upper bearing and lower arm bifurcated and detachably receiving a lower bearing, a drum having extensions on its ends journaled within the bearings, the drum having a seat, means at one end of the seat for connecting a flexible brake setting member thereto, a gear on the other end of the drum, and a manually operable gear member rotatable in the upper end of the bracket and meshing with said gear.

6. In a brake operating mechanism, a support, spaced bearings in the support, a drum with a gear wheel thereon and having its ends formed with extensions constituting trunnions journaled within said bearings, said drum having a seat means for connecting to the drum a flexible element adapted to be wound onto the seat, and means for rotating the drum comprising a rotatable member formed with teeth at one end meshing with the gear wheel on the drum, the other end being rotatably received in a bearing sleeve on the support, and means intersecting said sleeve and engaging a peripheral groove in the rotatable member for retaining it in place.

7. In a brake operating mechanism, a support, spaced bearings in the support, one of said bearings comprising a block detachably received in a bifurcated portion of the support, a drum having its ends formed with extensions constituting trunnions journaled within said bearings, said drum having a continuous flange defining a seat, means for connecting to the drum a flexible element adapted to be wound onto the seat, means for rotating the drum, and means for securing said removable bearing within the support.

8. In a brake operating mechanism, a support comprising a base, an arm depending therefrom and formed with a socket portion underlying said base, a bearing block received in said socket, means intersecting said socket and block for retaining the latter in position a rotatably mounted and positively driven drum of volute form provided at one end with means for attachment of a flexible element thereto and formed with a continuous flange defining a seat for the flexible element, said drum terminating at its ends in trunnions respectively mounted in the base and bearing block of the support.

In testimony whereof I affix my signature.
DONALD S. BARROWS.
